STRIPPING TOOL

Bernard Heilman, Detroit, Mich., assignor to
Leonard A. Young, Detroit, Mich.

Application January 13, 1941, Serial No. 374,257

15 Claims. (Cl. 15—140)

This invention relates to improvements in striping tools.

The main objects of this invention are:

First, to provide a hand striping tool of improved construction greatly facilitating the accurate and uniform application of paint stripes to angled objects, for example, metal frames, trimming and the like.

Second, to provide a device of the type described including an elongated handle or grip and a striping roller associated with the handle and rotatable on an axis parallel with the length of the handle whereby to make possible a more natural and less exacting movement of the operator's arm in manipulating the hand tool, with results which are greatly improved from the standpoint of ease, uniformity and evenness of deposition of the stripe, and ease and speed of operation.

Third, to provide a hand striping device for the application of striping material to angled objects, which enables the unfailing production of uniformly satisfactory striping jobs by relatively unskilled operators.

Fourth, to provide a hand striping tool of the character described having associated therewith an improved striping or paint applying roller which in cooperation with the features above noted furthers the uniformity of application of stripes to angled objects.

Fifth, to provide a striping device for manual use having a pigment applying roller of novel construction.

Sixth, to provide a striping device having gauge means and a pigment applying roller incorporated therein in a novel manner to increase the ease and speed of producing a satisfactorily uniform job.

Seventh, to provide a striping device of the above character having a pigment container associated therewith in a novel manner to prevent undesired changes in the consistency or quality of the pigment due to the heat of the operator's hand employed in manipulating the device.

Objects relating to details and economies of the invention will appear from the description to follow. The invention is defined and pointed out in the claims.

A structure embodying the features of the invention is illustrated in the accompanying drawing, wherein:

Fig. 1 is a view in side elevation partially broken away and in section to illustrate details

of construction and arrangement of the striping device of the invention.

Fig. 2 is an enlarged fragmentary view in section on line 2—2 of Fig. 3, further illustrating structural features of the device.

Fig. 3 is an enlarged view of the device along the line designated 3—3 in Fig. 2, with parts of the device removed and with the work operated on indicated by dotted lines.

Fig. 4 is a greatly enlarged view illustrating in section a portion of the striping roller and work to illustrate the construction of the paint or pigment applying roller.

Fig. 5 is an enlarged fragmentary view still further illustrating the construction of the applying roller of the present device and the manner in which it coacts with the work in insuring a uniformly copious distribution of paint or pigment thereon.

This invention relates generally to improvements in striping devices such as are employed in the application of paint stripes to angled structures such as frames, shelves and the like, in which operation it is necessary that a continuous uniform movement of the striping device be performed to the end that the application of the pigment will be uniform and free from spots or areas to which paint or pigment has been applied undesirably lightly or heavily. For this operation, strippers have heretofore been employed

in which a striping roller is mounted at one end thereof to rotate about an axis extending transversely of the length of the device, the device being manipulated somewhat in the manner of a paint brush. This type of device may be used with quite satisfactory results when plain surfaces are being treated. However, in applying a stripe running around a corner or around an angle, for example, such as the refrigerator shelf which I have illustrated in dotted lines in Fig. 3, difficulty has arisen heretofore because of the practical impossibility in using such striping devices for the operator to round the corner of the article in a single uninterrupted stroke of constant speed. The reason for this is that the arm extends longitudinally of the device and it is exceedingly difficult to guide the same while swinging the arm about the shoulder for the required uniform movement, without which deposition of the paint or pigment in local excessively heavy or excessively light areas inevitably results.

It is a primary object of my invention to provide a device in which these defects or objectionable features are not present, and one which is manipulated by a simple, wrist pivoting to round cor-

ners, although various other details thereof likewise contribute to the aforesaid desired result of a uniform continuous stripe for angled objects.

Referring to the drawing, the reference numeral 1 in general indicates the implement of the invention illustrated. This comprises an elongated cylindrical tubular body 2 adapted to be grasped by the user in the manner indicated in dotted lines in Fig. 1. This tubular body 2 is provided with a partition 3 separating the body into a paint or coating container portion or reservoir 4 from the grip portion 5. This arrangement serves to prevent the heat of the user's hand from affecting the consistency of the paint or coating material in the reservoir 4. This factor is of very substantial importance since the paint or coating material ordinarily employed in striping is subject to changing conditions as a result of even such heating as results from the hand of the operator grasping the implement where the reservoir extends into the grip portion as is quite common practice.

The reservoir 4 is provided with a filling dome 40 closed by the filler plug 6 and provided with the vent 7 which may be adjusted to enable efficient filling and also to enable the flow of the liquid pigment or coating material. The reservoir is provided with a detachable end closure plate 8 detachably secured by screws 42. The reservoir is also provided with a lateral discharge mouth or slot 9, the plate 8 constituting one side wall of this slot.

The edge walls 10 of the slot are extended into parallel ways 43 which slidably receive the gauging gate or slide 11 which is recessed at 44 on one side to receive the spring 45, taking up lost motion between the gate and its ways.

The striping roller 12 is journaled on the stub shaft or pin 13 so that it is supported within the slot or mouth 9 to project into the reservoir and to project from the slot. The body member has a relatively short laterally projecting nose 46 in which the slot is formed.

It will be noted that the roller 12 is retained on its stub shaft 13 by means of the end plate; also that the said adjusting or gauging member 11 is engaged with a lug 47 on the nut 14 so that the gauging member is retained by the removable end wall.

The adjusting screw 15 is rotatably mounted in the top wall of the reservoir to engage this nut member 14, the screw being provided with a knurled finger piece 16.

The gauging member is of general forked shape, its arms or forks being extended into the feed or discharge spaces between the periphery of the roller 12 and the edges of the discharge slot, as shown in Fig. 3, there being segmentally curved portions 48 coacting with opposed portions of the roller, as shown in Fig. 3.

The striping roller 12 has a concaved serrated periphery or face 18, the serrations being preferably of V-shape and extending entirely across the concaved face, as shown in Figs. 2, 4 and 5. This I find to be a matter of very substantial importance in that it enables the effective picking up of a substantial quantity of the pigment and the effective depositing thereof along the line of striping which in this case illustrated extends longitudinally of a groove 19 in a frame 20. With the face of the roller thus conformed, the pigment or coating material is effectively picked up from the reservoir and carried to the point of discharge where it is effectively discharged. The

gauging member can be adjusted to effectively gauge the amount.

The individual teeth of the roller perform a very effective delivery and distributing action, preventing the localized areas of insufficient or excessive pigment or coating.

As the thinning liquid commonly employed is highly volatile, it is a feature of great advantage to be able to thoroughly clean the device after it has been idle or when the use is discontinued. The removable end plate affords access to the movable and adjustable parts so that they can be effectively cleaned and the reservoir drained and cleaned.

To further insure accuracy and uniformity of deposition of the pigment, I provide the device of my invention with a gauge instrumentality including a work engaging finger 21 secured to a crosshead 22 which is slidably adjustable on the body of the instrument and maintained from rotation thereon by engagement with a longitudinally extending key 23 on the top of said body. A threaded screw 24 rotatable in said crosshead and threadedly engaging an enlargement or boss 25 on the front end of the tool body is employed for effecting accurate longitudinal adjustment of the positioning finger, being provided with an enlarged knurled portion 26 to facilitate this. In finally adjusted position of the gauge finger 21, the crosshead 22 may be clamped by means of a knurled screw 27 to lock the parts in desired position and enable large numbers of pieces to be striped without danger of dislocating the guide finger arrangement.

It will be apparent from the foregoing that I have provided a hand striping device which greatly facilitates the production of uniform striping jobs on irregularly shaped objects. As stated, it is exceedingly difficult to operate on angled objects with presently employed stripers and produce uniform results at the angles thereof, and a structure incorporating a striping roller journaled parallel to the length of the device overcomes this difficulty. The effectiveness of the result is furthered by the use of a striping roller of improved design which insures the presence of adequate striping material and simultaneously performs a local distributing action thereon as it is deposited. The mechanical difficulty of operating the device is further diminished by the adjustable guide feature, and the difficulty which has heretofore arisen because of the volatile nature of the striping liquid, and the fact that it has in hitherto known stripers been subjected to the heat of the operator's hand, is overcome by the arrangement of the pigment supply reservoir in my device.

I have illustrated and described my improvements in an embodiment which is very practical. I have not attempted to illustrate or describe other embodiments or adaptations as it is believed this disclosure will enable those skilled in the art to embody or adapt my improvements as may be desired.

Having thus described my invention, what I claim as new and desire to secure by Letters Patent, is:

1. A device for striping angled articles particularly facilitating production of a stripe of continuous uniform character around the angles of said articles, comprising an elongated hollow body having a grip portion adapted to be grasped by an operator, a reservoir for liquid striping material in said body, including a partition separating said reservoir from the grip portion, and a

striping roller journaled on said body remote from the grip portion on an axis extending parallel to the length of the body and offset laterally from the longitudinal axis thereof whereby to facilitate manipulation of the device about angles of the object to be striped by turning of the operator's wrist, said striping roller having a peripheral pickup and applying surface of serrated concave outline communicating laterally with said reservoir and insuring application of sufficient striping material to the object and uniform local distribution of the material along the length of the stripe.

2. A device for striping angled article particularly facilitating production of a strip of continuous uniform character around the angles of said articles, comprising an elongated hollow body having a grip portion adapted to be grasped by an operator, a reservoir for liquid striping material on said body, and a striping roller journaled on said body remote from the grip portion on an axis extending parallel to the length of the body and offset laterally from the longitudinal axis thereof whereby to facilitate manipulation of the device about angles of the object to be striped by turning of the operator's wrist, said striping roller having an applying surface communicating with said reservoir.

3. A device for striping angled articles particularly facilitating production of a continuous uniform stripe around the angles of said articles, comprising an elongated body support having a grip portion adapted to be grasped by an operator, a reservoir for liquid striping material carried by said support, and a striping roller communicating and fed by said reservoir and journaled on said support on an axis extending parallel to the length and offset substantially from the longitudinal center thereof whereby to facilitate manipulation of the device about angles of the object striped.

4. A striping apparatus for use on angled objects to enable the application of a uniform stripe by a continuous movement around the angles thereof, comprising a longitudinally extending body adapted to be grasped by an operator, an applying roller journaled on said body with its axis parallel to the length of the body, and means supplying striping material to said roller, said body having a work engaging gauge extending at an angle therefrom provided with a vernier adjustment for positioning the gauge longitudinally of the body and disposed to travel during the striping operation in a plane parallel to the surface being striped, with the gauge engaging a lateral side of the object and held thereagainst by thrust exerted longitudinally of the body.

5. A striping apparatus for use on angled objects to enable the application of a uniform stripe by a continuous movement around the angles thereof, comprising a longitudinally extending body adapted to be grasped by an operator, and an applying roller journaled on said body with its axis parallel to the length of the body, and means supplying striping material to said roller, said body having a work engaging gauge thereon and disposed to travel during the striping operation in a plane parallel to the surface being striped, with the gauge engaging a lateral side of the object and held thereagainst by thrust exerted longitudinally of the body, said gauge being positioned relative to said roller and body to enable the roller to be manipulated on said surface around an angle of the object, with the gauge in continuous operative engagement with

said side of the latter and without disturbing the operative engagement of the roller with said surface.

6. A striping device for striping angled objects, comprising an elongated body portion adapted to be grasped by an operator, said body portion having a paint reservoir therein and a roller journaled thereon in communication with paint in the reservoir on an axis extending parallel to the length of the body, and a work engaging gauge adjustable longitudinally on said body and extending therefrom at an angle to the axis thereof, said gauge being engageable with objects to be striped by pressure applied in the direction of the length of the body, said roller projecting beyond the outline of said body with the periphery thereof in approximate longitudinal alignment with said gauge, said gauge being positioned relative to said roller and body to enable the roller to be manipulated around an angle of said object with the gauge in continuous operative engagement with the object and without disturbing the operative engagement of the roller with a surface of the object.

7. A striping device for striping angled objects, comprising an elongated body portion adapted to be grasped by an operator, said body portion having a paint reservoir therein and a roller journaled thereon in communication with paint in the reservoir on an axis extending parallel to the length of the body, and a work engaging gauge adjustable longitudinally on said body and extending therefrom at an angle to the axis thereof, said gauge being engageable with objects to be striped by pressure applied in the direction of the length of the body, said roller being positioned relative to said roller and body to enable the roller to be manipulated around an angle of the object with the gauge in continuous operative engagement with the object and without disturbing the operative engagement of the roller with a surface of the object.

8. In a striping apparatus, the combination of an elongated body member having a grip portion at its rear end and a reservoir at its front end, said reservoir being provided with a delivery slot opening externally at an angle to the longitudinal axis of the body, a striping roller journaled in said slot to project therefrom and into said reservoir, there being feed spaces for the passage of material between the roller and the edge walls of the slot, the axis of said roller being parallel to the axis of said grip, and a manually adjustable gauging member having portions coacting with the periphery of said roller on opposite sides thereof and extending into the said feed spaces.

9. In a striping apparatus, the combination of an elongated body member having a grip portion at its rear end and a reservoir at its front end, said reservoir being provided with a delivery slot opening externally at an angle to the longitudinal axis of the body, and a striping roller journaled in said slot to project therefrom and into said reservoir, there being feed spaces for the passage of material between the roller and the edge walls of the slot, the axis of said roller being parallel to the axis of said grip.

10. In a striping apparatus, the combination of a body member having a grip and a reservoir, said reservoir being provided with a delivery slot, a striping roller journaled in said slot to project therefrom and into said reservoir, there being feed spaces for the passage of material between the roller and the edge walls of the slot, the face of said roller being transversely concaved and

provided with transverse serrations extending from side to side of the roller, a manually adjustable gauging member having portions coacting with the periphery of said roller on opposite sides thereof and extending into the said delivery spaces to regulate the thickness of striping material applied to the roller from the reservoir, and means for adjusting said gauging member portions in said spaces to adjust the width of the spaces between the roller and said portions.

11. In a striping apparatus, the combination of a body member having a grip and a reservoir, said reservoir being provided with a delivery slot, a striping roller journaled in said slot to project therefrom and into said reservoir, there being feed spaces for the passage of material between the roller and the edge walls of the slot, gauging means having portions coacting with the periphery of the roller and extending into said spaces, and means for adjusting said portions to simultaneously adjust the width of said spaces between the roller and said portions.

12. In a striping apparatus of the class described, the combination of an elongated tubular body member provided with a transverse partition, the portion of the body member at the rear of the partition constituting a grip and the portion at the front of said partition constituting a reservoir, said reservoir having a laterally disposed delivery slot, the edges of the walls of the slot being extended inwardly into parallel ways, a removable end plate for said reservoir constituting the outer wall of the slot, a striping roller having a transversely concaved periphery provided with uniform V-shaped serrations extending across the roller, said roller being journaled in said slot to project therefrom and to project into said reservoir on a stub shaft, the axis of which is parallel to the axis of the handle, the removable end plate constituting means for removably retaining said roller on its shaft, and a forked gauging member supported in said ways for manual manipulation and provided with opposed segmental gauging portions on the forks thereof cooperating with opposed portions of the periphery of said roller, said removable end plate constituting means for removably retaining said gauging member.

13. In a striping apparatus of the class described, the combination of an elongated tubular

body member provided with a transverse partition, the portion of the body member at the rear of the partition constituting a grip and the portion at the front of said partition constituting a reservoir, said reservoir having a laterally disposed delivery slot, the edges of the walls of the slot being extended inwardly into parallel ways, a removable end plate for said reservoir constituting the outer wall of the slot, a striping roller journaled in said slot to project therefrom and to project into said reservoir on a stub shaft, the axis of which is parallel to the axis of the handle, the removable end plate constituting means for removably retaining said roller on its shaft, and a forked gauging member supported in said ways for manual manipulation and provided with opposed segmental gauging portions on the forks thereof cooperating with opposed portions of the periphery of said roller, said removable end plate constituting means for removably retaining said gauging member.

14. In a striping apparatus of the class described, the combination of an elongated tubular body member provided with a grip portion at the rear end thereof and a reservoir at the front thereof, said reservoir having a laterally disposed delivery slot, the edges of the walls of the slot being extended inwardly into parallel ways, a striping roller having a transversely concaved periphery provided with uniform V-shaped serrations extending across the roller, said roller being journaled in said slot to project therefrom and to project into said reservoir, the axis of the roller being parallel to the axis of the handle, and a gauging member supported in said ways for manual manipulation to coact with said roller.

15. In a striping apparatus of the class described, the combination of an elongated tubular body member provided with a grip portion at the rear end thereof and a reservoir at the front thereof, said reservoir having a laterally disposed delivery slot, the edges of the walls of the slot being extended inwardly into parallel ways, a striping roller journaled in said slot to project therefrom and to project into said reservoir, the axis of the roller being parallel to the axis of the handle, and a gauging member supported in said ways for manual manipulation to coact with said roller.

BERNARD HEILMAN.
